Primary Examiner—Benjamin H. Layno[57] **ABSTRACT**

The method of the present invention involves a Twenty-One game, in which, in addition to his normal wager, a player will have the option of making an additional wager that becomes part of, and makes the player eligible to win, the progressive jackpot. If the player's Twenty-One hand comprises a particular, predetermined arrangement of cards, the player will win all, or part of, the amount showing on the progressive jackpot. In a Twenty-One game using any number of decks of cards, the predetermined winning arrangements of cards preferred in the present invention are an Ace, Two, Three, Four and Five suited; a Two, Three, Four and Five suited; a Four, Five and Six suited; a Four, Five and Six unsuited; an Ace-Jack suited; and optionally any Blackjack suited and any Blackjack unsuited. In a Twenty-One game that utilizes a six deck shoe, an alternative predetermined winning arrangements of cards preferred in the present invention are Five Three's unsuited; Three Five's suited; a Four, Five and Six suited; a Four, Five and Six unsuited and an Ace-Jack suited.

**METHOD OF PROGRESSIVE JACKPOT
TWENTY-ONE**

**CROSS REFERENCE TO RELATED
APPLICATIONS**

This application is a continuation of application Ser. No. 07/800,631 filed Nov. 27, 1991 and now U.S. Pat. No. 5,288,077; which is a continuation-in-part of application Ser. No. 07/361,276, filed Jun. 5, 1989 and now U.S. Pat. No. 5,078,405; which is a division of application Ser. No. 07/214,934, filed Jul. 5, 1988 and now U.S. Pat. No. 4,861,041; which is a continuation-in-part of application Ser. No. 07/182,374, filed Apr. 18, 1988 and now U.S. Pat. No. 4,836,553. The entire disclosures of each of the above-listed applications and patents are hereby incorporated by reference herein.

BACKGROUND OF THE INVENTION

U.S. Pat. No. 4,861,041 describes a method and apparatus for progressive jackpot gaming in which a separate bet is utilized in a Twenty-One game. As described in that patent, a player may make an additional wager to be eligible to participate in a separate progressive jackpot. If during the play of the normal Twenty-One game the player achieves a predetermined arrangement of cards, the player wins all or part of the progressive jackpot amount.

In a preferred embodiment of the invention as described in U.S. Pat. No. 4,861,041, the predetermined arrangement of cards that results in winning hands and the respective payoff amounts from the progressive jackpot in a Twenty-One game were as follows:

Winning Hand	Amount of Jackpot
Four 5's and an Ace	100%
Ace, two, three, four, five and six	4%
Six, seven and eight of same suit	100 tokens
Three 7's	50 tokens

In practice, however, it became apparent that this predetermined arrangement of cards as the winning hands affected the play of the normal Twenty-One game. If a player were attempting to achieve one of the winning jackpot arrangements, the player may have to make card selection, or "hit," decisions during the play of the Twenty-One game that would be detrimental to his chances of winning the normal Twenty-One game. For example, if "Four Fives and an Ace" wins 100% of the progressive jackpot, a player holding two Fives and an Ace (a hand count of 21) would have to take a "hit" if the player were attempting to win the progressive jackpot amount. Since a 21 hand count is a very strong hand in Twenty-One, a player taking a hit on a hand of two Fives and an Ace would be risking a hand count that at worst would result in a tie, or "push," with the dealer.

It is an object of the present invention to provide predetermined arrangements of cards that constitute winning hands for the progressive jackpot component of a Twenty-One game where the predetermined arrangement of cards does not affect the play of the normal Twenty-One game.

It is a feature of the present invention that a predetermined arrangements of cards that constitute winning hands for the progressive jackpot component of a

Twenty-One game (such as an Ace, Two, Three, Four and Five suited; a Two, Three, Four and Five suited; a Four, Five and Six suited; a Four, Five and Six un-suited; an Ace-Jack suited; any Blackjack Suited and any Blackjack, which are the preferred predetermined arrangements of cards when any number of decks are used) are selected so that the predetermined arrangement of cards does not affect the play of the normal Twenty-One game.

It is another feature of the present invention that a predetermined arrangements of cards that constitute winning hands for the progressive jackpot component of a Twenty-One game (such as Five Three's un-suited; Three Five's suited; a Four, Five and Six suited; a Four, Five and Six un-suited and an Ace-Jack suited, which are the preferred predetermined arrangements of cards when a six deck show is used) are selected so that the predetermined arrangement of cards does not affect the play of the normal Twenty-One game.

It is an advantage of the present invention that a player may attempt to achieve one of the predetermined arrangement of cards that will win all or part of the progressive jackpot component of the normal Twenty-One game without affecting the normal play of the Twenty-One game.

SUMMARY OF THE INVENTION

The method of the present invention involves a Twenty-One game, in which, in addition to his normal wager, a player will have the option of making an additional wager that becomes part of, and makes the player eligible to win, the progressive jackpot. If the player's Twenty-One hand comprises a particular, predetermined arrangement of cards, the player will win all, or part of, the amount showing on the progressive jackpot. In a Twenty-One game using any number of decks of cards, the predetermined winning arrangements of cards preferred in the present invention are an Ace, Two, Three, Four and Five suited; a Two, Three, Four and Five suited; a Four, Five and Six suited; a Four, Five and Six un-suited; an Ace-Jack suited; and optionally any Blackjack suited and any Blackjack un-suited.

In a Twenty-One game that utilizes a six deck shoe, an alternative predetermined winning arrangements of cards preferred in the present invention are Five Three's un-suited; Three Five's suited; a Four, Five and Six suited; a Four, Five and Six un-suited and an Ace-Jack suited.

**DETAILED DESCRIPTION OF THE
PREFERRED EMBODIMENTS**

The method of playing Twenty-One including a progressive jackpot component is described in detail in U.S. Pat. No. 4,861,041, which is incorporated herein by this reference thereto.

A conventional Twenty-One game is conducted on a gaming table. At the beginning of each hand, each player, in addition to making his usual wager for the play of the Twenty-One hand, may also make an additional wager to be eligible to participate in the progressive jackpot component of the game during that hand. Each wager made to be eligible for the progressive jackpot is added to the running total of the progressive jackpot amount.

The amount shown on the progressive jackpot meter will continue to increase for each gaming token wagered until a player achieves a winning hand. Predeter-

mined winning hands earn a player all or part of the amount shown on the progressive jackpot meter.

In a normal Twenty-One game, the dealer deals cards to the players and the dealer according to the normal method of play. One or more standard decks of playing cards may be used.

As discussed above, the preselected hands that are eligible for winning a portion of the progressive jackpot amount should not interfere with the play of the underlying Twenty-One game. In order to try and achieve a winning jackpot hand, a player should not have to choose between keeping a probable winning Twenty-One hand or taking additional cards to try and achieve a winning progressive jackpot hand. The preselected winning hands for the progressive jackpot should be hands that would otherwise be probable losing hands in the underlying Twenty-One game. This gives the player a second chance to win during the Twenty-One game and encourages player participation in the jackpot feature of the invention.

In a preferred embodiment of the present invention when the Twenty-One game uses any number of decks of conventional playing cards (from one deck to as many decks as the house desires to include in the game) which are then shuffled together, the preselected winning hands in a Twenty-One game are as follows:

TABLE 1

Winning Hand	Amount of Jackpot
Ace, 2, 3, 4 and 5 suited	highest amount
2, 3, 4 and 5 suited	second highest amount
4, 5 and 6 suited	third highest amount
4, 5 and 6 unsuited	fourth highest amount
Ace and Jack suited	fifth highest amount

As used in this Table 1, "suited" means that each of the designated cards must be of the same card suit—Spades, Hearts, Diamonds or Clubs. "Unsuited" means that the suit of the card is not relevant to determining whether a winning hand has been achieved; cards of the same suit or cards of different suits are equally eligible in the winning hand.

The amounts paid for the various winning hands are not critical but should be determined based on conventional percentage controls methods so that the house maintains a reasonable profit from the operation of the game. In most regulated gaming jurisdictions, the house percentage should not exceed 15% on a theoretical hold basis.

As an additional modification to this preferred embodiment, two additional preselected winning hands and payoff amounts may be added to this schedule:

TABLE 2

Additional Winning Hands	Amount of Jackpot
Any Blackjack suited	sixth highest amount
Any Blackjack unsuited	seventh highest amount

As used in this Table 2, "Blackjack" means a two card hand having an Ace and a ten count card (King, Queen, Jack or 10).

In a more preferred embodiment of the present invention when the Twenty-One game uses any number of decks of conventional playing cards (from one deck to as many decks as the house desires to include in the game) which are then shuffled together, the preselected winning hands and payoff amounts in a Twenty-One game are as follows:

TABLE 3

Winning Hand	Amount of Jackpot
Ace, 2, 3, 4 and 5 suited	100%
2, 3, 4 and 5 suited	2500 tokens
4, 5 and 6 suited	100 tokens
4, 5 and 6 unsuited	100 tokens
Ace and Jack suited	50 tokens

As used in this Table 3, "suited" means that each of the designated cards must be of the same card suit—Spades, Hearts, Diamonds or Clubs. "Unsuited" means that the suit of the card is not relevant to determining whether a winning hand has been achieved; cards of the same suit or cards of different suits are equally eligible in the winning hand.

As an additional modification to this more preferred embodiment, two additional preselected winning hands and payoff amounts may be added to this schedule:

TABLE 4

Additional Winning Hands	Amount of Jackpot
Any Blackjack suited	10 tokens
Any Blackjack unsuited	2 tokens

As used in this Table 4, "Blackjack" means a two card hand having an Ace and a ten count card (King, Queen, Jack or 10).

It has become popular to use six decks of standard playing cards, all shuffled together, and held in a card holding device known as a "shoe." In a preferred embodiment of the present invention when the Twenty-One game uses six decks of conventional playing cards shuffled together and held in a shoe, the preselected winning hands in a Twenty-One game are as follows:

TABLE 5

Winning Hand	Amount of Jackpot
Five 3's unsuited	highest amount
Three 5's suited	second highest amount
Four, Five and Six suited	third highest amount
Four, Five and Six unsuited	fourth highest amount
Ace and Jack suited	fifth highest amount

As used in this Table 5, "suited" means that each of the designated cards must be of the same card suit—Spades, Hearts, Diamonds or Clubs. "Unsuited" means that the suit of the card is not relevant to determining whether a winning hand has been achieved; cards of the same suit or cards of different suits are equally eligible in the winning hand.

The amounts paid for the various winning hands are not critical but should be determined based on conventional percentage controls methods so that the house maintains a reasonable profit from the operation of the game. In most regulated gaming jurisdictions, the house percentage should not exceed 15% on a theoretical hold basis.

In a more preferred embodiment of the present invention when the Twenty-One game uses six decks of conventional playing cards shuffled together and held in a shoe, the preselected winning hands and payoff amounts in a Twenty-One game are as follows:

TABLE 6

Winning Hand	Amount of Jackpot
Five 3's unsuited	100%
Three 5's suited	2500 tokens
Four, Five and Six suited	100 tokens

TABLE 6-continued

Winning Hand	Amount of Jackpot
Four, Five and Six unsuited	100 tokens
Ace and Jack suited	50 tokens

As used in this Table 6, "suited" means that each of the designated cards must be of the same card suit—Spades, Hearts, Diamonds or Clubs. "Unsuited" means that the suit of the card is not relevant to determining whether a winning hand has been achieved; cards of the same suit or cards of different suits are equally eligible in the winning hand.

In the event that two or more players achieve winning hand combinations during the same round of the Twenty-One game, the house can adopt appropriate tie-resolving rules. For example, players winning less than the full amount of the jackpot could be paid their winning amounts and a player winning the entire amount of the jackpot would then receive the remaining jackpot amount. Thus, the jackpot amount becomes the aggregate win amount that can be won during any one round of the Twenty-One game. This is similar to the conventional rules employed in a Keno game where the total amount available to win during any one Keno game is an aggregate amount with the smaller winnings being paid first and a player winning a large payout receives whatever is left of the aggregate amount.

While the invention has been illustrated with respect to several specific embodiments thereof, these embodiments should be considered as illustrative rather than limiting. Various modifications and additions may be made and will be apparent to those skilled in the art. Accordingly, the invention should not be limited by the foregoing description, but rather should be defined only by the following claims.

What is claimed is:

1. A method of including a jackpot component in a live casino table card game comprising the steps of:
  - (a) a player making a first wager to participate in the live casino table card game;
  - (b) a player optionally making a second wager to participate in the jackpot component;
  - (c) a dealer dealing a hand of playing cards to the player; and
  - (d) if the player's hand comprises a predetermined arrangement of cards, the player wins a predetermined percentage of the jackpot if the player has optionally made the second wager.
2. The method of claim 1, wherein any amount of the jackpot that is not won on the first hand carries over to the next hand.
3. The method of claim 1, wherein at least a portion of said second wager is added to said jackpot.
4. The method of claim 1, wherein at least a portion of said second wager is added to said jackpot and any amount of the jackpot that is not won on the first hand carries over to the next hand.
5. The method of claim 4, wherein at least a portion of said second wager in said next hand is added to said jackpot.
6. The method of claim 1, wherein at least a portion of said second wager is added to said jackpot and the next hand of the card game is played in accordance with steps (a) through (d) of claim 1.
7. The method of claim 6, wherein at least a portion of said second wager in said next hand is added to said jackpot.

8. The method of claim 1, wherein at least a portion of said second wager is added to said jackpot and any amount of the jackpot that is not won on the first hand carries over to the next hand which is also played in accordance with steps (a) through (d) of claim 1.

9. The method of claim 8, wherein at least a portion of said second wager in said next hand is added to said jackpot.

10. The method of claim 1, wherein the predetermined arrangement of cards comprises three 7's.

11. The method of claim 1, wherein the predetermined arrangement of cards comprises three 7's of the same suit.

12. The method of claim 1, wherein the predetermined arrangement of cards includes at least one 7.

13. The method of claim 1, wherein the predetermined arrangement of cards includes at least one 5.

14. The method of claim 1, wherein the live casino table card game comprises Twenty-One.

15. The method of claim 14, wherein the predetermined arrangement of cards comprises three 7's.

16. The method of claim 14, wherein the predetermined arrangement of cards comprises three 7's of the same suit.

17. The method of claim 14, wherein the predetermined arrangement of cards includes at least one 7.

18. The method of claim 14, wherein the predetermined arrangement of cards includes at least one 5.

19. A method of including a jackpot component in a live casino table card game comprising the steps of:

- (a) a player making a first wager to participate in the live casino table card game;
- (b) a player making a second wager to participate in the jackpot component;
- (c) a dealer dealing a hand of playing cards to the player; and
- (d) if the player's hand consists of a predetermined arrangement of cards, the player wins a predetermined percentage of the jackpot if the player has optionally made the second wager.

20. The method of claim 19, wherein any amount of the jackpot that is not won on the first hand carries over to the next hand.

21. The method of claim 19, wherein at least a portion of said second wager is added to said jackpot.

22. The method of claim 19, wherein at least a portion of said second wager is added to said jackpot and any amount of the jackpot that is not won on the first hand carries over to the next hand.

23. The method of claim 22, wherein at least a portion of said second wager in said next hand is added to said jackpot.

24. The method of claim 19, wherein at least a portion of said second wager is added to said jackpot and the next hand of the card game is played in accordance with steps (a) through (d) of claim 1.

25. The method of claim 23, wherein at least a portion of said second wager in said next hand is added to said jackpot.

26. The method of claim 19, wherein at least a portion of said second wager is added to said jackpot and any amount of the jackpot that is not won on the first hand carries over to the next hand which is also played in accordance with steps (a) through (d) of claim 1.

27. The method of claim 24, wherein at least a portion of said second wager in said next hand is added to said jackpot.

28. The method of claim 19, wherein the predetermined arrangement of cards consists of three 7's.

29. The method of claim 19, wherein the predetermined arrangement of cards consists of three 7's of the same suit.

30. The method of claim 19, wherein the predetermined arrangement of cards includes at least one 7.

31. The method of claim 19, wherein the predetermined arrangement of cards includes at least one 5.

32. The method of claim 19, wherein the live casino table game comprises Twenty-One.

33. The method of claim 19, wherein the predetermined arrangement of cards consists of three 7's.

34. The method of claim 19, wherein the predetermined arrangement of cards consists of three 7's of the same suit.

35. The method of claim 19, wherein the predetermined arrangement of cards includes at least one 7.

36. The method of claim 19, wherein the predetermined arrangement of cards includes at least one 5.

Primary Examiner—Michael O'Neill

[57] ABSTRACT

The method of the present invention involves a Twenty-One game, in which, in addition to his normal wager, a player will have the option of making an additional wager that becomes part of, and makes the player eligible to win, the progressive jackpot. If the player's Twenty-One hand comprises a particular, predetermined arrangement of cards, the player will win all, or part of, the amount showing on the progressive jackpot. In a Twenty-One game using any number of decks of cards, the predetermined winning arrangements of cards preferred in the present invention are an Ace, Two, Three, Four and Five suited; a Two, Three, Four and Five suited; a Four, Five and Six suited; a Four, Five and Six unsuited; an Ace-Jack suited; and optionally any Blackjack suited and any Blackjack unsuited. In a Twenty-One game that utilizes a six deck shoe, an alternative predetermined winning arrangements of cards preferred in the present invention are Five Three's unsuited; Three Five's suited; a Four, Five and Six suited; a Four, Five and Six unsuited and an Ace-Jack suited.
